JIG FOR SWIVEL LINKS

Catalino G. Tago, Brooklyn, N. Y.

Application August 13, 1946, Serial No. 690,199

2 Claims. (Cl. 90—12)

(Granted under the act of March 3, 1883, as
amended April 30, 1928; 370 O. G. 757)

1

This invention relates to a jig for holding a swivel link, and more particularly to a jig for holding a swivel link and for spot facing a portion of the link.

When a chain is attached to a stationary object, such as a wall, it is sometimes necessary to have the end link, which is secured to the wall, swiveled so that if the chain is rotated, it will not become twisted. The end link has an enlarged section capable of providing a bearing surface for the head of a swivel pin which is inserted through an opening in the enlarged section of the link. The bearing surface, which is internal in relation to the link, is difficult to machine. The present invention overcomes this difficulty by providing a jig comprising a movable yoked member which engages the end of the swivel link opposite to the enlarged section and which rotates the link against a cutter to machine the bearing surface.

An object of this invention is to provide a jig for holding a swivel link and capable of rotating the swivel link while causing an internal portion of the enlarged section of the link to be spot faced.

Another object is to provide a jig of this type having a cutter detachably affixed to the jig so that the internal portion of the link to be spot faced can be rotated in relation to the stationary cutter.

Another object is to provide a jig for holding and spot facing a swivel link, said jig having a replaceable guide shank for accommodating various sizes of links.

Further objects and advantages of this invention, as well as its construction, arrangement, and operation, will be apparent from the following description and claims in connection with the accompanying drawing, in which:

Fig. 1 is a view in elevation of a preferred form of the invention; and

Fig. 2 is a sectional view along line 2—2 of Fig. 1.

Jig 11, which may be made of metal or any other suitable material, includes a foundation 12, which is a relatively large, substantially rectangular member. Foundation 12 has centrally located in top face 13 an opening 14, which is substantially square in shape and which extends through foundation 12. Foundation 12 includes side 15 in which is centrally located opening 16, substantially round in shape and having its axis intercepting and perpendicular to the vertical axis of opening 14.

Foundation 12 has removably attached to it, shank 17. Shank 17 is an elongated member, 55

round in cross-section having ends 18 and 19. End 18 is offset so that it is substantially square in cross-section and is adapted to fit into opening 14 of foundation 12 with a relatively tight fit. End 18 has located in it opening 20, substantially round in shape and having the same diameter as opening 16 in foundation 12. Opening 20 is positioned so that when end 18 of shank 17 is inserted in opening 14 of foundation 12 with 5 which it mates, the axis of opening 20 of end 18 is aligned with the axis of opening 16 of foundation 12. Shank 17 is removably secured to foundation 12 by means of pin 21, which is adapted to be inserted through openings 16 and 20 with a relatively tight fit.

End 19 of shank 17 has in it opening 22. Opening 22 is substantially round in cross-section and extends through shank 17 at a point adjacent to end 19.

20 Jig 11 also includes cutter 23, which is a standard cylindrical cutting tool having at one end cutting teeth 24. Extending through cutter 23 along its cylindrical axis is opening 25 centrally located in cutter 23 and having a diameter 25 slightly larger than that of shank 17 so that it can be slipped over shank 17 in a relatively tight sliding fit. Cutter 23 also has extending therethrough perpendicular to its cylindrical axis an opening 26 substantially round in shape and of 30 the same diameter as opening 22 in shank 17 with which it is to be aligned. Cutter 23 is removably attached to shank 17 with teeth 24 facing foundation 12 by means of pin 27. Pin 27 is a cylindrical member having a diameter slightly smaller than opening 22 of shank 17 and opening 26 of cutter 23 so it can be inserted through these openings in a friction fit.

35 Jig 11 also includes yoke 28, which is a relatively large furcated member having sides 29, top face 30 and bottom face 31. Yoke 28 has slot 32 cut into and entirely across the bottom face 31. Opening 33 is substantially round in shape and extends through yoke 28 from side to side and is perpendicular to the longitudinal plane of slot 32. 40 The end of opening 33 is located on the vertical center line of face 29 and is adjacent to bottom face 31. Yoke 28 is rigidly affixed at its top face 30 to shaft 34 adapted for connection with a source of power (not shown) that is capable of 45 rotating shaft 34 and exerting a pull on it, thereby rotating and exerting a pull on yoke 28. The axis of shaft 34 forms the axis of the complete 50 jig and in assembled form is aligned with the longitudinal axis of link 38 and shank 17. Extending through opening 33 of yoke 28 is pin

35. Pin 35 is substantially cylindrical and has a shank 36 and one end offset to form enlarged head 37. Pin 35 has a diameter slightly less than opening 33 of yoke 28 and is adapted to fit therein in a relatively tight friction fit with the inner face of enlarged head 37 bearing on side 29 of yoke 28.

Jig 11 is designated to operate on a piece of work which is shown by way of illustration as being swivel link 38. Swivel link 38 is a chain link having one end enlarged to form section 39, through which is cut a central opening 40 adapted to have inserted in it a swivel pin (not shown) for securing the link to an object.

Jig 11 is designed to hold link 38 and to spot face the inner portion or back face of enlarged section 39. To assemble the jig end 18 of shank 17 is first inserted into opening 14 of foundation 12 keeping the axis of opening 16 of foundation 12 and opening 20 of shank 17 aligned. Pin 21 is inserted through these openings to rigidly secure shank 17 to foundation 12.

Link 38 is then positioned on shank 17 by inserting shank 17 into opening 40 of enlarged section 39, keeping end 19 of shank 17 protruding through enlarged section 39. Cutter 23 is then positioned on shank 17 by inserting shank 17 into opening 25 of cutter 23, keeping cutter teeth 24 in the downward position facing enlarged section 39 of link 38. Cutter 23 is then translated on shank 17 and rotated thereon until opening 26 of cutter 23 and opening 22 of shank 17 are aligned. Pin 27 is then inserted through the openings to secure cutter 23 rigidly in position on shank 17.

Yoke 28 is positioned with relation to link 38 by fitting link 38 into slot 32 so that opening 33 in side 29 of yoke 28 is clear with respect to link 38. Shank 36 of pin 35 is inserted through opening 33 and link 38 until the inner face of head 37 bears on side 29 of yoke 28 thereby affecting engagement of yoke 28 and link 38.

In operation when shaft 34 is rotated and pulled upon, link 38 also rotates and has a pull exerted on it. Cutter teeth 24 then come into contact with the inner face of enlarged link section 39. Enlarged link section 39 rotates in relation to stationary cutter 23 and this results in spot facing of the inner portion of section 39

5 by the action of cutter teeth 24 upon section 39. Shank 17 is removably affixed to foundation 12 so that it can be replaced with shanks of varying diameter for accommodating different sizes of swivel links. Jig 11 can be modified so that yoke 28 remains stationary while shank 17 and cutter 23 affixed thereon rotate in relation to enlarged section 39 of swivel link 38.

10 It is to be understood that various modifications and changes may be made in this invention without departing from the spirit and scope thereof as set forth in the appended claims.

15 The invention described herein may be manufactured and used by or for the Government of the United States of America for governmental purposes without the payment of any royalties thereon or therefor.

20 What is claimed is:

25 1. A jig for use in tooling a swivel link having a swivel-axis bore through one end, said jig comprising a shank for extending in axial and rotary sliding movement through the link bore, a tool fixedly mounted on the end of the shank extending into the link, said tool facing the link at the inner end of the link bore, means for supporting the end of the link opposite to the bore end, and means for locking the supporting means and link together for rotational movement.

30 2. In combination with a swivel link having a swivel-axis bore through one end, a jig for tooling said link, said jig comprising a shank for extending in axial and rotary sliding movement through said link bore, a tool fixedly mounted on the end of said shank extending into said link, said tool facing the link at the inner end of the link bore, means for supporting the end of said link opposite to the bore end, and means for locking the supporting means and link together for rotational movement.
